VALVE FOR ROCK DRILLS

Filed Nov. 5, 1926

UNITED STATES PATENT OFFICE.

FREDERICK W. RUDLIN, OF PHILLIPSBURG, NEW JERSEY, ASSIGNOR TO INGERSOLL-RAND COMPANY, OF JERSEY CITY, NEW JERSEY, A CORPORATION OF NEW JERSEY.

VALVE FOR ROCK DRILLS.

Application filed November 5, 1926. Serial No. 146,359.

This invention relates to rock drills, but more particularly to a distributing valve of the spool type for fluid actuated rock drills.

The objects of this invention are to obtain 5 an inlet valve which is quick and positive in action and which will increase the speed of the piston travel, cut down the consumption of pressure fluid and which will be economical of construction.

10 Further objects of this invention will hereinafter appear.

The invention consists of the combination of elements, features of construction, and arrangement of parts having the general 15 mode of operation substantially as herein-after described and more particularly pointed out in the appended claims, and illustrated in the accompanying drawings, in which

20 Figure 1 is a longitudinal sectional elevation showing the relative position of the moving parts when the piston is on its working stroke, and

25 Figure 2 is a similar view showing the relative positions of the moving parts when the piston is on its return stroke.

Referring more particularly to the drawings, the invention is shown embodied in a rock drill having a cylinder A, within which 30 is a reciprocatory hammer piston B having a forward extension or nose C which cooperates slidably with a front cylinder washer D seated in the front end of the cylinder A to form a closure therefor. The rearward 35 end of the cylinder is in this instance sealed by a back head E.

The back head E is shown solid and the nose C of the piston B is shown as a plain extension for the sake of simplicity of illustration.

40 In the present instance a valve chest F has a bore to receive bushings *p* and *o*, which form a valve chamber G of uniform diameter throughout its length. The valve chest F is preferably arranged longitudinally of the cylinder A and has an inlet connection H for the admission of pressure fluid to the chamber G' from a source of pressure fluid supply. The valve chest F may be either 45 formed integrally with the cylinder A or may be formed separately and secured in position in any suitable manner.

The chamber G is in this instance of uniform diameter throughout its length and is 55 open at its ends to receive sealing plugs J and

K, which may be held securely in place in any suitable manner.

Communication between the front and rear ends of the cylinder A and the chamber F is afforded by ports L and O which act as 60 inlet and exhaust ports alternately. Within the chamber F is a pressure fluid distributing valve P having a reduced central portion Q and end heads R and S which have actuating faces T and U respectively at their outer 65 ends against which pressure fluid may act to throw the valve in a manner to be described hereinafter.

The travel of the valve is limited by the stops J and K against which the actuating 70 faces T and U of the valve may strike. Between the chamber G and the cylinder bore A' are provided passages V, W, X and Y which cooperate with the valve P and the piston B in a manner to be hereinafter 75 described. Kicker ports Z and *a* are located intermediate the ports L and O. The ports W and X are so spaced with respect to each other that both may not be covered by the valve P simultaneously.

In the operation of the drill, with the valve P in the position indicated in Figure 1, the passages W and Y will be uncovered by the heads R and S respectively of the valve P. When the valve is in this position, 85 pressure fluid will flow from the chamber G through the passage W and the port L and into the rearward end of the cylinder bore A' impelling the piston forwardly. At the same time, pressure fluid is being exhausted 90 from the forward end of the cylinder by way of the port O and the passage Y to the atmosphere through exhaust port *b*. When the piston B has moved a sufficient distance in a forward direction, the passage Z is 95 opened and pressure fluid is admitted to an annular passage *c* into a chamber *d* where the face T of the valve P is exposed to the pressure fluid and the valve P is thrown forwardly, thus covering the passage Y and 100 opening the passages V and X.

In the position of the valve as illustrated in Figure 2, the passage X is uncovered for admitting pressure fluid to the forward end of the cylinder A and the piston B is forced 105 to the rear, due to the pressure on its forward face. The pressure fluid in the rearward end of the cylinder passes through port L, passage V and to the atmosphere through exhaust port *g*. As soon as the port 110

a is uncovered by the piston, live pressure fluid is admitted to an annular passage *e* and into a chamber *f* where the face *U* of the valve *P* is exposed to the pressure fluid 5 and the valve is thrown rearwardly covering passages *V* and *X* and opening passages *Y* and *W*, thus completing the cycle of operations.

The ports *L* and *O* are so placed with respect to the ends of the cylinder that a sufficient quantity of air is trapped by the piston on either its forward or its backward stroke to form a cushion for the piston. In normal operation, this air cushion overcomes the inertia of the piston in one direction and returns it in the opposite direction a sufficient distance to bring it under the control of the ports *O* or *L* as the case may be. If, however, the tool is allowed to stand idle for sometime the piston may take up a position too far forward or rearward to be under control of the ports *O* or *L*. To meet such a contingency, scratch passages *h* and *k* are provided as shown whereby pressure fluid 25 may be admitted to either face of the piston in order to return it to an operative position.

I claim:

1. In a rock drill, the combination of a cylinder, a hammer piston in the cylinder, a valve chest having a chamber, a valve in the chamber having a head at each end, an inlet port for admitting pressure fluid to the chamber between the heads, supply and exhaust passages leading from the chamber to the ends of the cylinder, said supply and exhaust passages being controlled by the heads, and kicker ports in the valve chest conveying pressure fluid from the cylinder 40 to the ends of the chamber for actuating the valve.

2. In a rock drill, the combination of a cylinder, a hammer piston in the cylinder, a valve chest having a chamber of uniform diameter throughout its length, a valve in the chamber having a head at each end, an inlet port for admitting pressure fluid to the chamber between the heads, supply and exhaust passages leading from the chamber 45 to the ends of the cylinder, said supply and exhaust passages being controlled by the end heads, and kicker ports in the valve chest

leading from the cylinder to the ends of the valve chamber for conveying pressure fluid to the said ends of the valve chamber for actuating the valve. 55

3. In a rock drill, the combination of a cylinder, a hammer piston in the cylinder, a valve chest having a chamber of uniform diameter throughout its length, a valve in the chamber having a head at each end, an inlet port for admitting pressure fluid to the chamber between the heads, supply passages leading from the chamber to the ends of the cylinder, exhaust passages leading 60 from the supply passages to the ends of the chamber, exhaust ports in the ends of the said chamber leading to the atmosphere, said supply and exhaust passages being controlled by the end heads of the valve, a kicker port leading from the front end of the cylinder to the front end of the valve chamber, and a second kicker port leading from the rearward end of the cylinder to the rearward end of the valve chamber for conveying pressure fluid to the ends of the valve chamber to act against the ends of the heads for actuating the valve. 70

4. In a rock drill, the combination of a cylinder, a hammer piston in the cylinder, a valve chest having a chamber, a valve in the chamber having a pair of end heads, an inlet port for admitting pressure fluid to the chamber between the heads, supply passages leading from the chamber to the ends of the cylinder, exhaust passages leading 80 from the supply passages to the ends of the chamber, exhaust ports in the ends of the said chamber leading to the atmosphere, said supply and exhaust passages being controlled by the end heads of the valve, a kicker port leading from the cylinder to the front end of the valve chamber, a second kicker port intermediate the first said kicker port and the rearward supply port leading to the rearward end of the valve chamber for conveying pressure fluid to the said ends of the valve chamber for actuating the valve, said end heads of the valve controlling communication between the exhaust ports and the 85 valve chamber ends of the kicker ports. 90

In testimony whereof I have signed this specification.

FREDERICK W. RUDLIN.
